UNITED STATES PATENT OFFICE

FRIEDRICH BANSEN, OF LEIPZIG, GERMANY, ASSIGNOR TO WILLY RABALD, OF LEIPZIG, GERMANY

SHEARING MACHINE

Application filed June 23, 1928, Serial No. 287,833, and in Germany February 16, 1927.

My invention relates to machines for shearing fur, plush, velvet, etc., for which I have made application for patent in Germany, February 16, 1927. In the following description, only fur will be mentioned but this is only by way of example and it is understood that my machine may be used for shearing any material. The machine is of the type in which the furs are engaged by positive means only while being presented to a shearing roller and otherwise are only moved by friction on a conveyer.

It is an object of my invention to improve a machine of this type so as to prevent damage to the furs and to this end I provide pairs of jibs having needles for positively engaging the furs, and I so operate these jibs that their needles are moved into positive engaging relation only when the fur is being presented to the shearing means.

Heretofore the furs were held by pins or by steel bands having sharp points which penetrate into the skin. It has also been proposed to hold the furs by suction through the medium of a perforated hollow cylinder. Pins or steel bands are objectionable as their manipulation requires considerable skill and often cause damage to the furs while a suction cylinder and its vacuum pump constitute an undesirable complication of the machine.

It has also been proposed to provide curved needle supports and to cause their needles to project from holes in a barrel of a guiding cylinder at given intervals but such needles make slotted holes in the fur which may detract considerably from its value.

These drawbacks are overcome in my invention. My machine is automatic to the elimination of the personal factor and the needles of the jibs are so advanced and retracted as to avoid damage to the furs by unduly extending the holes therein.

In a preferred embodiment of my inven-

tion I provide a guiding cylinder for the furs, or rather, the conveyer by which they are fed, the guiding cylinder being so arranged with respect to shearing means that it presents the fur to the means in proper position, and in flutes of this cylinder I provide pairs of jibs, each jib having a set of needles and the needles in the jibs of each pair projecting in opposite directions. Means are provided for displacing the jibs in opposite directions at a given moment, that is, when the fur is presented to the shearing roller, and the points of each two needles will then form V-shaped hooks for retaining the fur while it is being thus presented. Automatic means such as springs may be provided for returning the jibs and consequently the needles, to their initial positions.

It is another object of my invention to provide resilient means in combination with the fluted cylinder for exerting pressure on the fur while it is being gradually engaged by the needles and to this end I provide a roller having a liner of resilient material opposite the fluted cylinder. This is important as the thickness of the furs, and of a given fur at several points is subject to considerable variations. The resilient surface makes up for such variations and maintains uniform pressure.

In the drawing affixed to this specification and forming part thereof a machine embodying my invention is illustrated diagrammatically by way of example.

In the drawing

Fig. 1 is a diagrammatic elevation of the machine,

Fig. 2 is a cross section, and

Fig. 3 is a plan view drawn to a larger scale, of the end at which the fluted roller is carried.

Fig. 4 is a plan view of the fluted roller drawn to a still larger scale,

Fig. 5 is a detail illustration of one of the strips,

Fig. 6 is a corresponding illustration of the mating strip,

Figs. 7, 8 and 9, are sections on the corresponding lines in Fig. 4,

Fig. 10 is an elevation;

Fig. 11 is a plan view of one of the cams by which the jibs in the fluted roller are controlled,

Figs. 12 to 15 are details illustrating various relative positions of the strips in a pair.

Referring now to the drawing, 7 is a frame at one end of which a set of rollers is supported in suitable bearings 3, 3, 19 is a conveyer which moves toward the set of rollers in its upper and away from the set in its lower reach, as indicated by the arrows in Figs. 1 and 2, 20 is a tension roller at the end of the frame opposite to the set of rollers, 21 are brackets at either end of the frame, and 22 are threaded spindles inserted in the brackets and adapted to displace the roller, only one bracket and one spindle being shown in Fig. 1.

The set of rollers comprises a cutting roller 1; a fluted guiding cylinder 2 having trunnions 24; a guiding roller 6; the conveyor 19 moving about the fluted roller 2 and returning past the roller 6 as will appear from Fig. 2; a roller 18 provided with a lining 17 of resilient material, as rubber, arranged intermediate and above, the cylinder 2 and the roller 6; and rollers 4, 5 exerting pressure on the resilient liner 17.

7, 8 are jibs inserted in suitable flutes of the cylinder, 11 are blocks adapted to slide in the ends of each flute, one of the jibs being in direct contact with the corresponding slide 11 at one end and a spring 12 being inserted between the other end of the jib and the block 11 at that end. For the other jib, the arrangement is reversed as will appear from Fig. 4. 10, 10 are sleeves concealing the block 11 and the ends of the jibs at either end of the cylinder 2. The ends of the blocks 11 project at either end of the cylinder and cooperate with cams 13. 16, 16 are pins on the outer face of each cam by which the cams are held in the bearing 3, 3, 13^a is a slope, and 13^b is a step in the face of each cam as will appear from Figs. 10 and 11, the slope and the step pitched at about 180 degrees.

Each jib 8, 9 is provided with needles 14 and 15 inserted in suitable grooves in the inner faces of the jibs 8 and 9, respectively, as best seen in Figs. 12 and 13 from which it will also appear that the needles project in opposite directions in either jib, the needles 14 of the jibs 8 pointing to the right and the needles 15 of the jibs 9 pointing to the left. Obviously, the direction of the needles may be reversed in the jibs.

In the normal position of the needles, that is, when the ends of the blocks 11 for the corresponding pairs of jibs move on the parallel faces of the cams 13, 13, the needles 14, 15 are in the position illustrated in Figs. 5 and

14, in which their ends meet. The cylinder rotates clockwise. When during such rotation the blocks 11 of a given pair of jibs ascend the slopes 13^a on the cams 13 which occurs at about the same time as the pair of jibs under consideration enters the zone in which the roller 18 begins to exert pressure on the fur between its liner 17 and the fluted cylinder 2, the blocks gradually move inwards and each block displaces that jib with which it is positively connected while compressing the spring 12 of the other jib. The jibs therefore move in opposite directions causing the needles 14 and 15 to penetrate the fur in opposite directions also and after such penetration has been completed, forming V-shaped hooks as indicated in Figs. 6 and 15. The jibs remain in this position and retain the fur on the fluted cylinder until their blocks reach the step 13, which they descend abruptly. It follows that the needles will penetrate the skin gradually under the influence of the slope 13^a so that the skin is not torn by needles, and will be retracted suddenly when the blocks arrive at the set 13^b. While the needles penetrate into the skin, the fur is retained by the resilient liner of the roller 18 so that the fur does not recede before the points of the needles but is penetrated properly.

I wish it to be understood that I do not desire to be limited to the exact details of construction shown and described for obvious modifications will occur to a person skilled in the art.

I claim:—

1. A shearing machine comprising shearing means and means for presenting an object to said shearing means, said presenting means having a pair of jibs, each jib having a set of needles, the needles in each set projecting in opposite directions, means for imparting movement in opposite directions to said jibs, and means for timing the movement of said jibs with respect to the operation of said presenting means.

2. A shearing machine comprising shearing means, a conveyer adapted to present articles to said shearing means, a cylinder adjacent said shearing means and adapted to support said conveyer, pairs of jibs in said cylinder, each jib in a pair having a set of needles projecting in opposite direction to the needles of the other jib, means for exerting pressure on said conveyer, and on said cylinder, means for imparting movement in opposite directions to said jibs, and means for timing the movement of said jibs with respect to the action of said pressure-exerting means.

3. A shearing machine comprising shearing means, a conveyer adapted to present articles to said shearing means, a cylinder adjacent said shearing means and adapted to support said conveyer, pairs of jibs in said cylinder, each jib in a pair having a set of needles projecting in opposite direction to the

needles of the other jib, means for exerting pressure on said conveyer, and on said cylinder, a block arranged at either end of each pair of jibs in said cylinder, each block engaging one of said jibs positively, a spring inserted between said block and the other jib, and a stationary cam adapted to cooperate with each set of blocks.

4. A shearing machine comprising shearing means, a conveyer adapted to present articles to said shearing means, a cylinder adjacent said shearing means and adapted to support said conveyer, pairs of jibs in said cylinder, each jib in a pair having a set of needles projecting in opposite direction to the needles of the other jib, a roller having a liner of resilient material and arranged to exert pressure on said conveyor, on an article on said conveyor and on said cylinder, means for imparting movement in opposite directions to said jibs, and means for timing the movement of said jibs with respect to the action of said resilient liner.

5. A shearing machine comprising shearing means, a conveyer adapted to present articles to said shearing means, a cylinder adjacent said shearing means and adapted to support said conveyer, pairs of jibs in said cylinder, each jib in a pair having a set of needles projecting in opposite direction to the needles of the other jib, a roller having a liner of resilient material and arranged to exert pressure on said conveyor, on an article on said conveyor and on said cylinder, rollers adapted to exert pressure on said liner, means for imparting movement in opposite directions to said jibs, and means for timing the movement of said jibs with respect to the action of said resilient liner.

40 6. A shearing machine comprising shearing means, a conveyer adapted to present articles to said shearing means, a cylinder adjacent said shearing means and adapted to support said conveyor, pairs of jibs in said cylinder, each jib in a pair having a set of needles projecting in opposite direction to the needles of the other jib, means for exerting pressure on said conveyer, and on said cylinder, a block arranged at either end of each pairs of jibs in said cylinder, each block engaging one of said jibs positively, a spring inserted between said block and the other jib, a sleeve at either end of said cylinder for holding said blocks in position radially, and a stationary cam adapted to cooperate with each set of blocks.

65 7. A shearing machine comprising shearing means, a cylinder arranged opposite said shearing means, needles on said cylinder projecting in opposite directions and means for moving said needles in opposite directions during the shearing operation and for returning said needles into their initial position after the shearing operation has been completed.

8. A shearing machine comprising shearing means, a cylinder arranged opposite said shearing means, needles on said cylinder projecting in opposite directions and a cam having a slope for gradually moving said needles in opposite directions during the shearing operation and a step for abruptly returning said needles into their initial position after the shearing operation has been completed.

In testimony whereof I affix my signature.

FRIEDRICH BANSEN.
